UNITED STATES PATENT OFFICE.

EDWARD L. SILL, OF WOODWARD, OKLAHOMA, ASSIGNOR TO E. L. SILL MANUFACTURING COMPANY.

HORSE-COLLAR.

1,356,407.

Specification of Letters Patent.

Patented Oct. 19, 1920.

Application filed September 13, 1918. Serial No. 253,921.

To all whom it may concern:

Be it known that I, EDWARD L. SILL, a citizen of the United States, residing at Woodward, in the county of Woodward and State of Oklahoma, have invented a new and useful Horse-Collar, of which the following is a specification.

The device forming the subject matter of this application is a horse collar, and the invention aims to provide novel means for assembling with the body portion of the collar, detachably, the covering wherein the pad proper is housed.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings:

Figure 1 is a rear elevation of the collar, parts being broken away;

Fig. 2 is an end elevation of the collar;

Fig. 3 is a cross section taken approximately on the line 3—3 of Fig. 1.

Fig. 4 is a sectional detail enlarged from Fig. 3 and showing the means whereby one edge of the covering is assembled with one of the shells of the collar;

Fig. 5 is a transverse section showing the means whereby the other edge of the covering is assembled with the shell of the collar;

Fig. 6 is a fragmental top plan of the covering or casing wherein the pad is enclosed.

Fig. 7 is a plan view looking at the under side of the covering which houses the pad.

In carrying out the present invention there is provided a pair of shell members 1 and 2 which preferably are made of metal and, roughly speaking, are trough-shaped in cross section. At their inner edges, the peripheries of the shell members 1 and 2 are bent outwardly to form hame-receiving lips 3, assuming that the present construction is to be employed on a hame collar. The upper ends of the shell members 1 and 2 are united

by a hinge 4 of any desired construction. The outer edges of the shells 1 and 2 are bent inwardly to form underlying gripping flanges 5. Secured to the concaved surfaces of the shells 1 and 2 and disposed transversely thereof are clips 6, spaced apart, and extended in spaced relation from one end of the shells 1 and 2 to the other, the clips 6 terminating in hook-shaped heads 7 disposed adjacent the points where the body portions of the shell members 1 and 2 merge into the hame-receiving lips 3. The lower end of the shell 1 is provided with an extension or guide 10 within which the lower end of the shell 2 is received.

From what has been stated hereinbefore, it will be obvious that the shells 1 and 2 may be swung apart and be swung together on the hinge 4, and when the shells are swung together, the lower end of the shell 2 is received within the extension or guide 10 on the shell 1.

Any suitable means 11 may be provided whereby the lower ends of the shells may be detachably locked together.

The invention comprises a casing made up of two members 34 and 35 which may be fashioned from leather or any other flexible material having the necessary strength. The member 34 of the casing co-operates with the shell 1, and the member 35 of the casing co-operates with the shell 2. Ribs 36, which may be strips of leather, are stitched to the inner edges of the casing members 34, these ribs being received in the hook-shaped heads 7 of the clips 6. Attached by stitchings 37 or otherwise to the outer edges of the casing members 34 and 35 are longitudinal tongues 38 which may be made of leather. The tongues 38 are received beneath the gripping flanges 5.

A strip 39 extends transversely of the casing member 34 at the upper end thereof and is stitched to the said member or otherwise attached thereto, as shown at 40. One end of the strip 39, which may be made of leather, forms a projecting tongue 42. There are eyelets 43 in the strip 39 and eyelets 44 are formed in the member 35. Through the eyelets 43 and 44 is passed a lacing cord 45 and, through the instrumentality of the lacing cord 45 and the strip 39, the casing members 34 and 35 are detachably connected at their upper ends. The end 42 of the strip 39 is adapted to be bent over to extend

underneath the hinge 4 which unites the upper ends of the shells 1 and 2, this operation and construction being clearly evident when Fig. 7 is compared with Fig. 1.

5 Disposed within the compartment defined by the shell 1 and the casing member 34, and by the shell 2 and the casing member 35 is a tubular canvas cover 46, which may be reinforced adjacent its top by a transverse 10 strip 47. In the top of the cover 46 is a slit 48 about which is secured a reinforcement 49 of leather or the like, the reinforcement having eyelets 50 through which is extended a lacing cord 51. The slit 48 permits an 15 inflatable tube 52 to be inserted into the cover 46, the tube 52 preferably being made of rubber, and by tightening up the lacing cord 51, the slit 48 may be substantially closed.

20 A neck bridge 60 may be held by means of straps 61, or in any other suitable way, to the upper portion of the collar, as is common in the art.

The operation of the structure has been 25 dealt with hereinbefore, step by step, but briefly considered is as follows:—

The inflatable tube 52 is inserted into the cover 46 through the slit 48, and the lacing cord 51 is tightened up, the stem 54 projecting through one end of the cover. The ribs 36 are assembled with the clips 6. The cover 46, inclosing the tube 52, is placed in the shells 1 and 2. The end 42 of the strip 39 is carried over the top of the cover 46 35 beneath the hinge 4. The longitudinal tongues 38 on the members 34 and 35 of the casing are engaged with the flanges 5 of the shells 1 and 2, and thus the structure is disposed in condition for use.

40 When the tube 52 is inflated sufficiently,

the tongues 38 are held securely engaged with the gripping flanges 5, and the ribs 36 are held firmly engaged with the heads 7 of the clips 6.

Having thus described the invention, what 45 is claimed is:—

1. A horse collar comprising a shell provided along its inner edge with a continuous hame receiving lip; a hook shaped clip secured to the shell and having its free edge 50 projecting in the same direction as the lip in alinement therewith, a casing having one edge extending between the free edge of the clip and the shell; a rib on the casing and received within the clip; means for securing the outer edge of the casing to the outer edge of the shell; and a pad within the casing.

2. A horse collar comprising shells; a hinge uniting the upper ends of the shells; 60 casing; means for releasably connecting the longitudinal edges of the casings with the longitudinal edges of the shells; a pad located between the shells and the casings; a flexible strip permanently secured to the under side of one casing below the top thereof and extended beyond the said casing to form a laterally projecting tongue extended upwardly and transversely of the pad and extended beneath the hinge, between the hinge 70 and the pad; and means for securing the tongue detachably to the other casing.

In testimony that I claim the foregoing as my own, I have hereto affixed my signature in the presence of two witnesses.

EDWARD L. SILL.
